Attorneys.

Patented May 19, 1925.

Des. 67,329

UNITED STATES PATENT OFFICE.

WILLIAM HENRY BAGBY, OF LOS ANGELES, CALIFORNIA.

DESIGN FOR A FRAME FOR A NUTCRACKER.

Application filed July 19, 1922. Serial No. 3,130. Term of patent 3½ years.

To all whom it may concern:

Be it known that I, WILLIAM H. BAGBY, a citizen of the United States, residing at Los Angeles, in the county of Los Angeles and State of California, have invented a new, original, and ornamental Design for a Frame for a Nutcracker, of which the following is a specification.

Reference is had to the accompanying drawings forming a part of the specification, in which:

The figure is a perspective view of the frame for a nut cracker showing my new and ornamental design.

I claim:

The ornamental design for a frame for a nut cracker as shown.

WILLIAM HENRY BAGBY.
